(57) **CLAIM**

We claim the ornamental design for an illuminated responsive display on a joystick, as shown and described.

DESCRIPTION

FIG. 1 is a top view of an illuminated responsive display on a joystick showing our new design, showing a typical location of illumination on the illuminated responsive display when the joystick is in a first position;

FIG. 2 is a top view thereof, showing an alternate typical location of the illumination on the illuminated responsive display when the joystick is in a second position;

FIG. 3 is a top view thereof, showing an alternate typical location of the illumination on the illuminated responsive display when the joystick is in a third position;

FIG. 4 is a top view thereof, showing an alternate typical location of the illumination on the illuminated responsive display when the joystick is in a fourth position;

FIG. 5 is a top view thereof, showing an alternate typical location of the illumination on the illuminated responsive display when the joystick is in a fifth position; and,

FIG. 6 is a top view thereof, showing an alternate typical location of the illumination on the illuminated responsive display when the joystick is in a sixth position.

The surface shade lines shown between the outer circumference of the illuminated responsive and the first set of the inner broken lines depict a translucent portion of the illuminated responsive display. The broken lines showing remainder of the joystick are for environmental purposes only and form no part of the claimed design.
